[57] **CLAIM**

The ornamental design for a work support belt, as shown and described.

DESCRIPTION

FIG. 1 is a top, front perspective view of a work support belt, showing my new design;

FIG. 2 is a bottom plan view of the support belt as shown in FIG. 1;

FIG. 3 is a front elevational view of the support belt as shown in FIG. 1;

FIG. 4 is a rear elevational view of the support belt as shown in FIG. 1;

FIG. 5 is a front elevational view of another embodiment of the support belt as shown in FIG. 1 having shoulder straps; and,

FIG. 6 is a rear elevational view of the support belt as shown in FIG. 5.

FIG.4

FIG.3

FIG.2

FIG.1

FIG.5

FIG.6
